UNITED STATES PATENT OFFICE.

ALFRED D. CHANDLER, OF CHELMSFORD, MASSACHUSETTS.

YARN-SEPARATOR FOR SPINNING-FRAMES.

SPECIFICATION forming part of Letters Patent No. 476,731, dated June 7, 1892.

Application filed August 25, 1890. Serial No. 363,055. (No model.)

To all whom it may concern:

Be it known that I, ALFRED D. CHANDLER, a citizen of the United States, residing at Chelmsford, in the county of Middlesex and 5 Commonwealth of Massachusetts, have invented a certain new and useful Improvement in Yarn-Separators for Spinning-Frames, of which the following is a specification.

My invention relates to yarn-separators for 10 spinning-frames or devices adapted to be arranged between adjacent spindles of a spinning-machine to prevent interference between the yarns being spun and wound upon such spindles; and the object of said invention is 15 to prevent the yarns being caught on the ends of the separator-blades; to permit the use of a very light traveler and a very high speed of the spindle; to permit the use of a very wide separator-blade, thus insuring a more perfect 20 separation of the yarns; to enable the separator-blades to be quickly placed in a position where they will not interfere with the operation of doffing and to retain them in such 25 position by their own weight and to enable said separator-blades quickly to return to their normal position; to enable all the separator-blades to be removed from the spinning-frame, when desired, quickly and without the removal of or loosening of screws or other fastenings, and to secure means of ready adjustment 30 of the length of the traverse of the separator-blades and their shortest distance from the ring-rail.

In the accompanying drawings, Figure 1 is 35 a front elevation of a part of a ring-spinning frame, showing the roller-beam, thread-board, finger-board, guide-rail, spindle-rail, ring-rail, lifting-rod, cross-shaft and its arm, spindles, bobbins, cops, and separators, and a part of 40 the devices which connect the separators to each other and a part of the devices which operate said separators; Fig. 2, a vertical section on the line 2 2 in Fig. 1, showing a left-side elevation of my improvement and its 45 supporting and operating parts, the position of the separator-blade in the operation of doffing being shown in dotted lines and in its normal position by full lines; Fig. 3, a front elevation of the bracket of the separator-bar, 50 parts of said bar, the separator-rod, its adjustable collar and adjustable foot; Fig. 4, a left-side elevation of the socket-piece which is

carried by the separator-rod; Fig. 5, an isometric view of the bracket which forms a lock-hinge with said socket; Fig. 6, an isometric 55 view of the upper part of the adjustable foot of the separator-rod; Fig. 7, an isometric view of the lower part of said foot; Fig. 8, an isometric view of the bracket or stand which guides the separator-rod; Fig. 9, a side elevation of either of the anti-friction rolls, one of which raises the separator-rod, while the other raises the lifting-rod; Fig. 10, a front elevation of the last-named anti-friction roll and the stud which carries said roll; Fig. 11, a side 60 elevation of a collar arranged between said anti-friction roll and the nut which holds the stud upon which said anti-friction roll turns in the cross-shaft arm.

The roller-beam A, thread-board B, hinged 70 to the roller-beam, finger-boards B', hinged to the thread-board, the yarn-guides or "pig-tails" b, secured to the finger-boards, the ring-rail C, the lifting-rod c, guided in the spindle-rail D and the lower or guide rail E, the latter 75 serving as a step-rail where the spindles have an upper and a lower bearing, the cross-shaft F, turning in brackets f, secured to the guide-rail E, and caused to rock by the usual means and provided with the cross-shaft arm f', the 80 free end of which carries a horizontal stud f'', on which turns an anti-friction roll f'', said roll being arranged under and supporting a lifting-rod c, the spindles G, their rings g, 85 their bearings g', and bobbins H, are all of the usual construction and operation as used in ring-spinning machines. The yarn y descends from the drawing-rolls (not shown) through the yarn-guides, and thence through the travelers c', which run on the rings g, secured to the ring-rail C in the usual manner, 90 and is wound in cops Y on the bobbins H or on cop-tubes in the usual manner.

For economy of space the spindles are set as near together as possible, and the yarns 95 being wound on adjacent spindles are thrown outward by centrifugal force and are apt to strike each other and be broken, the tendency of the yarns to strike each other being greater the lighter the travelers and the greater the 100 speed of the spindle. It is therefore customary to use separators or thin sheets or blades of metal in spinning-frames run at a high rate of speed, the yarn striking the separators and

being thereby prevented from striking each other. The yarns when flying outward, when free to do so, describe the surfaces of imaginary inverted balloons, the balloons being largest when the ring-rail is in its lowest position and the yarns being in the greatest danger of striking each other at the largest horizontal diameters of the balloons so described and the larger diameters of said balloons rising as the ring-rail rises. Separators permanently affixed to the ring-rail cause the ring-rail by their own weight to sag between the lifting-rods, of which there are two or more to each ring-rail or section thereof, requiring the ring-rail to be made stronger and therefore heavier.

Separators movable independently of the ring-rail but in some cases receiving a part of their motion from the ring-rail have been used. These are liable to bend the ring-rail between the lifting-rods and retard the ring-rail when they first come in contact therewith and make uneven cops. Such movable separators are commonly pivoted back of and above the ring-rail and are swung out of the path of the ring-rail when the latter is in or near its highest position, there being less need of separators at such times, and are commonly so narrow vertically, in order that they may not strike against the thread-board and roller-beams in rising, that the yarns interfere above and below the separators when in working position. The yarn frequently catches on the ends of the separators when the separators are leaving and returning to their working position.

Separators which cannot be moved out from between the spindles are in the way during the operation of doffing. The separators described below obviate these objections. The separators proper are of sheet metal and are secured to a separator-bar J, which extends back of the ring-rail parallel therewith and is provided with as many brackets K as there are separator-rods N, (hereinafter described,) each bracket K being secured to the separator-bar J, as by screws k, and having laterally-projecting pins k' k², the pin k' being parallel with the axis of said bar J and entering a backwardly-inclined slot l, having a half-round lower end in the top of the socket-piece L and serving as a pivot on which said separator-bar J may be given a partial revolution about the axis of said pin k' to raise the separators out of the way before doffing and to restore them to position afterward. Each socket-piece L is provided in front of the inclined slot l with a curved projection l', the curvature of which is concentric with the rounded lower front end of the slot l and at a distance from said lower end of said slot equal to the space between the pins k' k², so that when the separators are turned down into the position shown in Fig. 2 the pin k² rests upon a shoulder l², arranged on the front of the socket-piece at the lower end of the projection l', which prevents the sep-

rators going below a horizontal position. Each socket-piece is provided with an upwardly-projecting stop l³, preferably cast in one piece with said socket-piece, arranged back of the slot l, and adapted to be struck by the separator-bar J when the separators are turned up from between the spindles to prevent the further backward movement of the separators and to support them in their raised position, the center of gravity of the combined separator-bar and separators being at this time a little back of the axis of the pivot-pin k'. When the separators are in their horizontal position, the projection l' and the backward inclination of the slot l prevent the separator-bar from being disengaged from the socket-piece; but when the separators are in their raised position the separator-bar may be lifted, drawing the pivot-pins out of the inclined slots, and removed, with the attached separators, from the machine for repairs or for other purposes.

Each socket-piece L is provided with a collar l⁴, adapted to receive and fit the upper end of a vertical separator-rod N, and is held in place on said rod by a set-screw l⁵, which turns in said collar and thrusts against said rod. There are as many separator-rods as there are lifting-rods, and each separator-rod is guided vertically, sliding in the sleeves m m' of the stand or bracket M, secured to the guide-rail by bolts m², as shown in Fig. 1, and is raised precisely as a lifting-rod is raised—that is, by the rising of the cross-shaft arm f', the stud f² being lengthened and projecting backward through said arm to support an anti-friction roll f⁴, which is a duplicate of the roll f³ above referred to. The stud f² is passed through a slot f⁵ in the cross-shaft arm up to a stationary annular shoulder f⁶, with which said stud is provided, and a nut f⁷ is turned up on the said stud against the opposite face of said arm in the usual manner. One of the anti-friction rolls is retained on said stud between said shoulder f⁶ and the head of a screw f⁸, (shown by dotted lines in Fig. 10,) which enters a threaded hole in the end of said stud, also in the usual manner, and the other of said rolls is retained on said stud by the nut above named and another nut f⁹, which turns on the reduced and threaded other end f¹⁰ of said stud, collars f¹¹ f¹² being arranged between said last-named roll and said nuts to lessen friction.

Each separator-rod is provided with an adjustable foot O, formed in two parts o o', the upper o of which (see Fig. 6) has a collar o² integral therewith, which receives the lower end of the separator-rod N and is held thereon by a set-screw o⁴, which turns in said collar and thrusts against said rod. The lower part o' of the foot (see Fig. 7) is an angle-piece, the horizontal portion o³ of which is arranged above the anti-friction roll f⁴ in a position to be raised by the rising of said roll. The parts o o' are each slotted vertically at o⁶ o⁷, and are secured to each other by

a bolt o^8 , passing through said slots, and a nut o^5 , turning on the threaded end of said bolt against the lower part o' of said foot. The parts of the foot are prevented from turning on each other by vertical ribs on their contiguous faces, the ribs o^{10} on the part o being arranged to enter between the ribs o^9 on the part o' . By loosening the nut o^5 and adjusting the parts of the foot vertically on each other the highest point of the traverse of the separators is varied or the lowest point of said traverse; but the lowest point is preferably determined by an adjustable collar P , which slides on the separator-rod N and is held at any required height by a set-screw p , said collar by striking the top of the bracket M preventing any further downward movement of the separator-rod. The largest diameter of the balloon described by the yarn between the traveler and the yarn-guide or pigtail of course has a much less traverse than the ring-rail, being above the ring-rail when the ring-rail is down and at all other times and never rising as high as the guide-wire, the largest diameter of the balloon diminishing as the ring-rail rises and rising more slowly than the ring-rail rises; but it is not sufficient that the separator should separate the yarns merely at the largest diameter of the balloon, because if the separator is too narrow—as, for instance, if it were a single horizontal wire—the yarns would on a long traverse interfere above and below the separator when the balloons were largest. The separator in practice is therefore adjusted to stand between the largest diameters of adjacent balloons and is wide enough to extend above and below such largest diameters for a sufficient distance when the ring-rail is at its lowest position and to rise with such largest diameters until the ring-rail has reached its highest point. The fact that the separators above described do not in their usual operation swing upward upon pivots enables them to be of much greater width vertically than the vertically-swinging separators commonly employed—at least twice as wide as such swinging separators. The increased width of the separators allows of a shorter traverse of the separators and prevents the yarn from interfering above and below the separators when the ring-rail is in its lowest position and the balloons are largest. The use of wider separators enables longer cops to be spun. The backward inclination of the slot l , the curved projection l' and its distance from the lower end of said slot, and the shoulder l'' hold the separator-bar very securely in the horizontal position of the separators.

6c The separating devices above described can be used equally well in spinning either warp or filling.

I claim as my invention—

1. The combination of the spindles, the ring-rail, the separators, the means for imparting a vertical traverse to said ring-rail and separators, and adjustable stops to vary the limit of the

downward movement of said separators, as and for the purpose specified.

2. The combination of the spindles, the ring-rail, the separators, the separator-bar, the separator-rods, means for imparting a vertical traverse to said ring-rail and separator-rods, said separator-rods being adjustable in length to vary the limit of the upward movement of said separators, and adjustable stops to vary the limit of the downward movement of said separators, as and for the purpose specified.

3. The combination of the spindles, the ring-rail, the separators, the separator-bar, the separator-rods, means for imparting a vertical traverse to said ring-rail and separator-rods, said separators being arranged and adapted to remain between said spindles during the entire traverse of said ring-rail and said separator-rods being adjustable in length to vary the limit of the upward movement of said separators, and adjustable stops to vary the limit of the downward movement of said separators to vary the length of the traverse of said separators without affecting the length of the traverse of said ring-rail, as and for the purpose specified.

4. The combination of the spindles, the ring-rail, vertical separator-rods, means for giving said ring-rail and separator-rods a vertical traverse, separators, the separator-bar operated by said separator-rods, stands in which said separator-rods are guided, and stop-collars secured on said separator-rods above said stands and by striking on the tops of said stands adapted to limit the downward movement of said separator-rods, as and for the purpose specified.

5. The combination of the spindles, the ring-rail, vertical separator-rods, means for giving said ring-rail and separator-rods a vertical traverse, separators, the separator-bar operated by said separator-rods, stands in which said separator-rods are guided, and stop-collars secured on said separator-rods above said stands and by striking on the tops of said stands adapted to limit the downward movement of said separator-rods, said collars being adjustable on said rods to vary the length of the traverse of said rods, as and for the purpose specified.

6. The combination of the spindles, the ring-rail, the vertical separator-rod having a foot adjustable in length, the separators, the separator-bar operated by said rod, and the cross-shaft having an arm provided with a stud which extends under said foot, as and for the purpose specified.

7. The combination of the spindles, the ring-rail, the vertical separator-rod, a foot secured to said rod and formed in two parts, each provided with a slot, a bolt arranged in said slots to secure the parts thereof to each other and to allow the same to be adjusted on each other, the separators, the separator-bar operated by said rod, and the cross-shaft having an arm provided with a stud which extends under said foot, as and for the purpose specified.

8. The combination of a separator-bar having journals or pivot-pins, separators carried by said bar, separator-rods having sockets to receive said journals and to enable said separators to be turned into or out of their operative position, means for retaining said journals in said sockets when said separators are in an operative position, and means for allowing said journals to be detached from said sockets when said separators are turned out of said operative positions, as and for the purpose specified.

9. The combination of the separator-bar, separators carried thereby, the separator-rod, a socket secured thereto and provided with an inclined slot and with a curved projection concentric with said lower end of said slot, and a bracket secured to said separator-bar and having pins, one of which enters said slot to enable said bar and separators to be turned thereon and the other of which normally engages said projection, but is disengaged therefrom by turning said bar to allow said pin first named to be disengaged from said slot and said separator-bar to be disconnected from said separator-rod, as and for the purpose specified.

10. The combination of the separator-bar, separators secured thereto, the separator-rod,

a socket secured rigidly thereto, a bracket secured to said separator-bar and having a pin which turns in said socket to enable said separators to be moved into a horizontal position or at will into a vertical position, and a stop arranged on said socket to engage said bar and to support said separators in a raised position, as and for the purpose specified.

11. The combination of the spindles, the ring-rail, means for giving the same a vertical traverse, the vertical separator-rod, a foot secured to said rod and formed in two parts, each provided with a slot, and a bolt arranged in said slots to secure the parts thereof to each other and to allow the same to be adjusted vertically on each other, each part of said foot being provided with vertical ribs and the ribs on one of said parts entering between the ribs on the other of said parts to prevent them from turning on each other, as and for the purpose specified.

In witness whereof I have signed this specification, in the presence of two attesting witnesses, this 21st day of August, A. D. 1890.

ALFRED D. CHANDLER.
